ZENKICHI ONO, OF MASURY, OHIO.

VEGETABLE-CUTTING MACHINE.

No. 852,844.

Specification of Letters Patent.

Patented May 7, 1907.

Application filed June 11, 1906. Serial No. 321,201.

To all whom it may concern:

Be it known that I, ZENKICHI ONO, a subject of the Emperor of Japan, residing at Masury, Trumbull county, State of Ohio, 5 United States, have invented a new and useful Improvement in Vegetable-Cutting Machines, of which the following is a specification.

My invention relates to improvements in 10 vegetable cutting machines in which a slicing knife may be used either alone or in conjunction with a series of knives, (hereinafter designated for convenience of reference "subsidiary knives"), having their blades at right 15 angles, or substantially so, to the plane of the slicing knife and to the cutting edge thereof. And the objects of my improvement are:—1st, to provide an apparatus for cutting certain vegetables or fruits rapidly 20 and uniformly, and in a variety of shapes, as in slices, strips, cubes or rectangular or diamond shaped lozenges; 2nd, to provide an apparatus by which such objects may be cut both horizontally and vertically by a single 25 movement; 3rd, in such an apparatus, to provide an adjustable and reversible table, and means to secure readily the same in the position in which it may be placed for operation; and 4th, to provide a means whereby 30 all of said knives may be securely fastened in place in the apparatus, but whereby said subsidiary knives may be readily removed, if desired. I obtain these objects by the 35 mechanism illustrated in the accompanying drawings in which,—

Figure I is a plan of the implement set for the combined use of the slicing knife and the subsidiary knives. Fig. II is a longitudinal section of the implement set for the same 40 use.

Similar letters refer to similar parts throughout the several views.

K K L M constitute the frame of the machine, the sides K K of which are slightly 45 flexible laterally.

N N are legs raising the end of the machine which is toward the operator for convenience of using. The same purpose, however, may be served by continuing the frame end M 50 downward beyond the frame proper and dispensing with the legs N N.

J is a board or table permanently fixed to the sides K K and the end L of the frame. The under surface of J is preferably beveled 55 at its inner end, and to this end the slicing knife D is attached by two screws h h. For

greater firmness this knife is also attached to and supported by the frame sides K K by means of the tenons d d.

A is an adjustable board or table attached 60 to the sides K K of the frame by the pivots H H. By means of this pivotable arrangement, the table A (hereinafter for convenience of reference designated as the "tilting table"), may be depressed at the inner end, 65 or it may be turned completely over, thus reversing the upper and lower sides.

E E E are a series of tooth like blades set into the end of the tilting table A, and at right angles, or substantially so, to the plane 70 of the slicing blade and to the cutting edge thereof. The shape of these subsidiary knives is not important. In the drawings they are shown as triangular, which is perhaps the most desirable shape. In order to secure 75 a smooth surface for the vegetable to pass over in the process of cutting, these knives are set into the end of the tilting table A, and, projecting below it, are bent at a right angle, and fastened to the under end of the table by 80 the screws j j j. In the drawings these knives are shown each made and attached separately, and for ease in removing and sharpening or replacing, this is the most desirable construction, although the knives 85 may be made and attached in pairs, in triplets or in any other combination without changing the substantial character of my invention.

I is a spring attached to the frame end M 90 and pivoted thereon by means of the screw i. The function of the spring I is to return the tilting table A to its primary position in the same plane as the table J, when, in the operation of the machine the subsidiary knives E 95 E E are being used. When it is desired to reverse the table A, the spring I is swung parallel to the frame end M and may be allowed to remain in this position while the slicing knife D is alone being used.

G is a bolt or rod passing transversely through the frame sides K K and through one or the other of the holes or slots g g in the tilting table A. One end of the said bolt or rod has an angular shoulder, a, which sets 105 into a corresponding socket in one of the frame sides K and thus prevents the rod turning when the nut or thumb screw F is turned. The other end of said rod or bolt is threaded and provided with a nut or thumb screw F under which may be placed, if desired, a metal plate or washer f.

The two holes or slots *g g* pass transversely through the tilting table *A*, parallel to its axis and equidistant therefrom. They may be of any desired shape but must be larger, 5 in the direction of motion of the tilting table *A*, than the diameter of the bolt *G*. By tightening the thumb screw *F*, the sides *K K* of the frame are forced against the edges of the tilting table *A*, which is thereby secured 10 at any desired position within the limits of its motion permitted by the relative diameters of the bolt *G* and the hole or slot *g*.
k is a groove running longitudinally along the inner sides, *K K*, of the frame.
15 *B* and *C* are two blocks lying across the tables *A* and *J* respectively, and sliding thereon. These two blocks *B* and *C* are connected by a light rod *m* passing through both at right angles to the frame sides *K K*. Said 20 rod *m* is bent at right angles upon emerging from the blocks *B* and *C*, and slides in the groove *k* acting as a guide for the blocks *B* and *C* as they are moved back and forth upon the tables *A* and *J*. It is not necessary, however, 25 that the rod *m* pass completely through the blocks *B* and *C*. The rod *m* passes through the slot *b* in the block *B*, permitting the under surface of said block to follow the surface of the table *A*, when the latter is depressed at the inner end, as in Fig. 2.
30 *e e e* are grooves in the block *B* corresponding in number and position to the subsidiary knives *E E E* and so arranged that when the block *B* is pressed against the said subsidiary knives *E E E*, the latter may be completely housed within said block.

To use the implement for slicing purposes the tilting table *A* is set with the smooth side uppermost, as in Figs. 3 and 4, and is securely 40 fixed in the desired position by tightening the thumb screw *F*. The thickness of the slices to be produced will depend upon the amount of depression of the inner end of the tilting table *A* below the knife *D*. The block *B* is then drawn back over the table toward 45 *M*, the vegetable to be sliced is placed upon the table *A*, between the knife *D* and the block *B*, and the latter is slid forward against the knife *D* cutting from the lower side of the 50 vegetable a slice which drops into a suitable receptacle below. Or the block *B* may be pushed up over the table *J*, leaving the table *A* clear, and the vegetable then may be pressed along the table *A* against the knife *D*, by the hand alone.
55

To use the implement for any purpose other than slicing, the table *A* is reversed as in Figs. 1 and 2. For cutting into strips the table may be depressed and locked by the 60 thumb screw as in the first process. The vegetable is placed upon the table *A*, between the knife *D* and the block *B*, in the same position as before and being pressed by the block *B* against the knives *D* and *E E* *E* is cut both horizontally and vertically by

the one movement. The portions cut drop into a receptacle below in the form of rectangular strips. Or the block *B* may be pushed up over the table *J*, leaving the table *A* clear, and the vegetable then may be pressed along the table *A* against the knives *D* and *E E E*, by the hand alone. 70

To use the implement for cutting into cubes or lozenges, the table *A* is set with the knives uppermost as in the last above case, 75 but the thumb screw *F* is loosened and the spring *I* set into position over the end of the table *A*, which may then be depressed by pressure upon its inner end but will return by reason of the spring *I* to its primary position in the same plane with the table *J* when the pressure is removed. The block *C* is then slid toward the end *L* of the frame, the vegetable is placed on the table *J*, between the knives *E E E* and the block *C*, which is 80 then pressed against said knives *E E E*, cutting the vegetable vertically to the height of said knives. The vegetable is then turned on its vertical axis 90° , and is placed on the tilting table *A*, between the knives *E E E* and the block *B*, which is then pushed with a slightly downward pressure against the knives *D* and *E E E*. The vegetable will then be cut into small cubes which will drop into a suitable receptacle below. If instead of 95 turning the vegetable 90° for the second cutting it be turned a less amount, the vegetable will be cut into diamond shaped lozenges. 100

I claim:—

1. In a vegetable cutter the combination of a fixed table bearing at one end a slicing knife lying in the same plane as the top of said table, and forming a continuation thereof, with a tilting table lying, when in its primary position, in the same plane as the fixed table and making a continuation thereof, but which may be depressed a short distance by pressure at the end adjacent to the fixed table, two or more subsidiary knives, whose planes lie parallel to one another and at right angles, or substantially so, to the plane of the slicing knife and to the cutting edge thereof, attached to the tilting table at the end adjacent to the slicing knife, and a spring to return said tilting table to its primary position when the pressure is removed. 105

2. In a vegetable cutter the combination of a fixed table bearing at one end a slicing knife lying in the same plane as the top of said table and forming a continuation thereof, with a tilting table having its under side plain and bearing on the upper side a series of two or more subsidiary knives set parallel to one another at or near the end of the tilting table adjacent to the slicing knife and having the planes of said subsidiary knives at right angles, or substantially so, to the plane of the slicing knife and to the cutting edge thereof, a frame, slightly flexible laterally, surrounding 115 120 125 130

and supporting both of said tables, pivots passing through the frame and into the tilting table upon which the latter may be turned a half revolution thus reversing the under and upper sides, a longitudinal groove on the inner side of said frame, two blocks whose inner faces lie parallel to each other and are held always at the same distance apart by a light rod bent in the form of a rectangle, passing longitudinally through both of said blocks and running in said groove, one of said blocks lying and sliding upon the fixed table and the other of said blocks lying and sliding upon said tilting table, slots in said tilting table block corresponding with the subsidiary knives, and in which, when said block is pressed against the said subsidiary knives, the latter may be completely housed, a rod or bolt, threaded on one end and having an angular shoulder at the other end passing through the frame and through a transverse hole or slot in the tilting table, a socket corresponding to said angular shoulder and in which the latter sits in one side of the frame, and a compression nut turned on the threaded end of said rod against the other side of said frame, under which compression nut a metal plate or washer may be placed, if desired.

30 3. In a vegetable cutter the combination of a fixed table, bearing at one end a slicing knife blade lying in the same plane with the

top of said table, and forming a continuation thereof, with a tilting table lying when in its primary position, in the same plane with the 35 fixed table and making a continuation thereof, but which may be depressed a short distance by pressure at the end adjacent to the fixed table, two or more subsidiary knife blades, whose planes lie parallel to one another and at right angles, or substantially so, to the plane of the slicing knife blade and to the edge thereof, attached to the tilting table at the end adjacent to the slicing knife blade, a spring to return said tilting table to its primary position, when pressure is removed, two 40 blocks whose inner faces lie parallel to each other and are held always at the same distance apart by suitable connections, one of said blocks lying and sliding upon the fixed 45 table and the other of said blocks lying and sliding on said tilting table, slots in said tilting table block corresponding to said subsidiary knives and in which, when said block is pressed against the subsidiary knives the 50 latter may be completely housed.

In testimony whereof, I have signed my name to this specification in the presence of two subscribing witnesses, this sixteenth day of May 1906.

ZENKICHI ONO.
